UNITED STATES PATENT OFFICE.

VINCENT BENDIX, OF CHICAGO, ILLINOIS.

ENGINE-STARTER.

1,134,975.

Specification of Letters Patent.

Patented Apr. 6, 1915.

Application filed August 10, 1914. Serial No. 856,055.

To all whom it may concern:

Be it known that I, VINCENT BENDIX, a citizen of the United States, residing at Chicago, in the county of Cook and State 5 of Illinois, have invented certain new and useful Improvements in Engine-Starters, of which the following is a specification.

My invention relates more particularly to a starter for a gas engine and the like characterized by the employment of a screw shaft operated by a motor and a pinion screw-threaded upon the shaft and adapted to travel longitudinally in one direction along the shaft into engagement with a rotatory member of the engine to be started and to travel longitudinally in the opposite direction after being thrown out of engagement with the engine member when the engine begins to run on its own power.

The object of this invention is to provide efficient and positive stops for the last mentioned longitudinal movement of the pinion on its shaft, these stops being of such character that all binding between the pinion 20 and its shaft is prevented so that when the shaft is rotated the pinion will properly advance longitudinally into engagement with said engine member as intended. While the same character of stop may be used at the other end of the screw shaft the same is not necessary because the engine member when it starts its rotations on its own power exerts sufficient force upon the pinion to dislodge it if there should be any binding between it and the screw shaft of this extreme travel of the pinion.

In the drawings, Figure 1 is a sectional elevation of an engine starter embodying my invention and illustrating the preferred form thereof; Fig. 2 a section on the line 2—2 of Fig. 1; Fig. 3 a similar section but illustrating the pinion at its extreme inward travel; Fig. 4 is an end elevation of the pinion but showing the weight removed; Fig. 5 a sectional elevation of the corresponding parts shown in Fig. 1, with the exception that the screw shaft has a single screw thread instead of the triple threads of Fig. 1; Figs. 6, 7 and 8 views corresponding to Figs. 2, 3 and 4, with the exception that they apply to the modified form of screw shaft of Fig. 5; Fig. 9 a sectional elevation of a screw shaft and pinion illustrating a modified form of stop; Fig. 10 an end elevation of the pinion of Fig. 9; Fig. 11 a sectional elevation on the line 11—11 of

Fig. 9; Fig. 12 a sectional elevation of another modified form of stop; Fig. 13 a sectional elevation on the line 13—13 of Fig. 12; Fig. 14 an elevation of the pinion of Fig. 12; Fig. 15 a sectional modification of still another modified form of stop; Fig. 16 a sectional elevation on the line 16—16 of Fig. 15 looking in the direction of the arrow and illustrating a face view of the stop member on the screw shaft; and Fig. 17 a face view of the pinion of Fig. 15 illustrating the stop member thereon.

My invention in its broader aspect may partake of different forms and in the accompanying drawings I have illustrated several of many practical and efficient constructions.

Speaking in general terms, the essence of my invention consists in providing stops which contact at such angle as not to cause a binding of one with the other, whereby the pinion is always free to move longitudinally of the screw shaft when the latter is rotated in the starting operation. The preferred form 75 of stop is illustrated in Figs. 1 to 8 but the other or modified forms embody the same invention in its broader aspect.

Referring to the construction illustrated in Figs. 1 to 4 the screw shaft 1 is mounted 85 within the casing 2 and rotated by means of a suitable prime mover such as the electric motor 3 through the medium of suitable driving connections which need not be here explained as they form no part of the invention. The intermediate portion of the screw shaft is screw-threaded being preferably provided with triple threads 1^a. The extreme outer end of the shaft which is reduced in diameter is provided with other 95 and ordinary threads 1^b which run in the opposite direction to the threads 1^a. Upon the outer threads 1^b is screwed a bearing sleeve 4 provided with the thrust flange 4^a against which the outer face of the pinion 5 contacts at its extreme outward travel. The pinion is screw-threaded upon the threads 1^a of the screw shaft and is therefore correspondingly provided with triple threads.

Explaining the operation of the parts as thus far described, the rotation of the screw shaft by the motor 3 will cause a longitudinal movement of the pinion 5 in a direction to the right in Fig. 1, that is outwardly in 100 this particular construction, with the result that the pinion will mesh with a rotatable

member of the engine to be started which, in the present instance, is the fly wheel 6 provided with a circular rack or gear 6^a. After the pinion is in mesh with the fly wheel it will come in contact with the thrust bearing sleeve 4 and will then rotate in unison with the screw shaft whereupon the engine will be rotated through the medium of the fly wheel. When the engine starts to run on its own power the increased rate of rotation imparted to the pinion by means of the fly wheel will cause the pinion to move longitudinally in the opposite direction along the screw shaft, that is to the left in Fig. 1 or 10 inwardly in this particular construction. In practice the pinion will be thus automatically unmeshed from the fly wheel by this longitudinal movement and will thereupon momentarily rotate with the screw shaft 15 after clearing the inner face of the fly wheel, after which when the speed of rotation of the screw shaft decreases the pinion will at times move to its extreme inward travel. Without the use of proper stops for the 20 travel of the pinion in this latter direction the pinion would be apt to bind upon the screw shaft so that when the shaft is thereafter rotated to repeat the engine starting operation the pinion would rotate with the 25 screw shaft and not move longitudinally outward as intended. The stop device provided for preventing any such binding will now be described.

The screw threads 1^a or rather the grooves 30 in the shaft to form the screw threads 1^a terminate abruptly at their inner ends to form shoulders 1^c. Inasmuch as the threads shown are triple threads there are three of these shoulders 1^c. In like manner the triple 35 threads of the pinion instead of tapering or running out to nothing preferably terminate in abrupt shoulders 5^a, as seen in Fig. 4, which shoulders come into contact in unison with the shoulders 1^c of the screw 40 shaft. All of the shoulders or rather the members of each pair of shoulders present surfaces substantially parallel to each other when contacting thereby causing the proper 45 stopping of the pinion without any possibility of binding of the pinion on the screw shaft. Moreover, by the use of triple threads and the consequent equidistant spacing of the stop members circumferentially around the screw shaft a three-point contact is provided thereby assisting in the preventing of 50 binding action and the strain or pressure is distributed equally around the circumference of the screw shaft. The pinion at the end of its travel in the opposite direction, that is at the end of its outward travel in the present instance, has a three-point bearing against the thrust sleeve 4 by reason of the provision of the triple threads, and the pinion is thereby properly centered and 55 the pressure distributed equidistantly around

the flange 4^a of this thrust sleeve. While stop members may be provided at this end of the screw shaft similar to the stops 1^c the same are not necessary inasmuch as the engine can dislodge the pinion and cause it to move longitudinally of the shaft even if it should become bound thereon by frictional engagement with the thrust sleeve. 70

In Figs. 5 to 8 I have shown a construction which is the same as that of Figs. 1 to 75 4 with the exception that the shaft 7 corresponding to the shaft 1 has a single screw thread 7^a and a single stop shoulder 7^b at its inner end. Likewise the pinion 8 has a single stop shoulder 8^a. 80

In Figs. 9, 10 and 11 I have shown a modified form of stop for the longitudinal movement in one direction of the pinion 9 upon its screw shaft 10 consisting of a pin 11 located at the end of the groove forming the screw threads of the shaft. This pin as shown in Fig. 11 is screw-threaded into the screw shaft 10 with its head projecting above the surface of the groove so as to be contacted by the end 9^a of the pinion. This end 9^a forms a stop shoulder adapted to operate with the pin 11 by acting at substantially right angles thereto to constitute a positive stop for the pinion without any binding effect. 90

In Figs. 12, 13 and 14 I have shown another modified form of construction for the pinion 12 upon its screw shaft 13. The stop device consists of two stop members, one being a pin 14 somewhat similar to the pin 11 but projecting outwardly to a greater distance than the latter so as to be in a position to be contacted by a pin 15 carried by the pinion 12 and projecting laterally from its inward face. In this construction the 105 thread of the pinion is not utilized as one of the stop members but the special pin 15 is provided. 95

In Figs. 15, 16 and 17 I have shown still another modified form of stop for the pinion 16 on its screw shaft 17. In this construction the stop member on the screw shaft consists of a clutch-shaped disk 18 and the stop member on the pinion consists of a correspondingly shaped clutch face 19 which 110 members are adapted to contact each other with their stop shoulders moving against each other in the same direction, that is face to face, so as to avoid any binding of the pinion upon the screw shaft. 120

I claim:

1. An engine starter comprising, in combination with a member operatively connected with the engine, a motor, a driving member adapted to coöperate with and drive 125 said engine member but normally out of engagement therewith, a rotatable member which is driven by the motor and on which the driving member is mounted for rotary and also for longitudinal movement, where- 130

by when said rotatable member is rotated the driving member is automatically moved longitudinally thereof in one direction into driving engagement with said engine member and whereby the difference in speed between the engine when started on its own power and said motor automatically moves the driving member longitudinally in the other direction and out of its said driving engagement, and means for stopping the longitudinal movement of said driving member in the latter direction and preventing binding thereof.

2. An engine starter comprising, in combination with a member operatively connected with the engine, a motor, a driving member, adapted to coöperate with and drive said engine member but normally out of engagement therewith, a rotatable shaft which is driven by the motor and on which the driving member is screw-threaded for rotary movement therewith and also for longitudinal movement in one direction for engagement between the driving member and the engine member and in the other direction for disengagement between said parts, and a stop on the shaft for stopping such latter longitudinal movement of the driving member and preventing binding thereof.

3. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, and means on the screw shaft for stopping the pinion in its movement in the last named direction and preventing binding thereof.

4. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, and a stop on the shaft adapted to be contacted by the pinion in its movement in the last named direction to stop it and prevent binding thereof.

5. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, and a stop for the pinion in its move-

ment in the last named direction, acting at substantially right angles to a part of the pinion.

6. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, said pinion and shaft having coöperating stop members arranged to contact when the pinion reaches its extreme travel

7. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, and a stop for the pinion in its movement in the last named direction, located at the end of the thread of the screw shaft and adapted to be contacted by the end of the thread of the pinion.

8. An engine starter comprising, in combination with a member operatively connected with the engine, a motor, a shaft driven thereby and having a screw-threaded portion, and a pinion screw-threaded on said shaft and adapted to travel longitudinally thereon and out of engagement with the engine member when the engine runs on its own power, one end of the thread of the shaft terminating abruptly to form a shoulder which the thread of the pinion strikes at its said extreme travel and by which such travel is stopped.

9. An engine starter comprising, in combination with a member operatively connected with the engine, a motor, a shaft driven thereby and having a screw-threaded portion, and a pinion screw-threaded on said shaft and adapted to travel longitudinally thereon and out of engagement with the engine member when the engine runs on its own power, one end of the thread of the shaft terminating abruptly to form a shoulder and the corresponding end of the thread of the pinion also terminating abruptly to form a shoulder, said shoulders constituting coöperating stop members.

10. An engine starter comprising, in combination with a member operatively connected with the engine, a motor, a shaft driven thereby and having a plurality of screw-threads, and a pinion screw-threaded thereon with corresponding plurality of screw-threads, one end of the threads of the screw shaft formed as stops for stopping the

pinion in its longitudinal movement on the shaft.

11. An engine starter comprising, in combination with a member operatively connected with the engine, a motor, a shaft driven thereby and having a plurality of screw threads, and a pinion screw-threaded thereon with corresponding plurality of screw threads, one end of the threads of the screw shaft terminating in shoulders forming stops for stopping the pinion in its longitudinal movement on the shaft.

12. An engine starter comprising, in combination with a member operatively connected with the engine, a motor, a shaft driven thereby and having a plurality of screw threads, and a pinion screw-threaded thereon with corresponding plurality of screw threads, one end of the threads of the screw shaft terminating in shoulders forming stops for stopping the pinion in its longitudinal

movement on the shaft, and the corresponding end of the threads of the pinion terminating in shoulders forming stops co-operating with the other stops, the different stops being arranged to contact in unison.

13. An engine starter comprising, in combination with a member operatively connected with the engine, a motor, a shaft driven thereby and having a threaded portion, a pinion screw-threaded on the shaft and adapted to travel longitudinally in both directions thereon, in one direction into engagement with the engine member and in the other direction out of engagement therewith, and coacting stops on the shaft and pinion respectively for stopping the travel of the pinion in its last-named direction.

VINCENT BENDIX.
